UNITED STATES PATENT OFFICE.

JOHANNES PIETER VAN GELDER, OF GRANVILLE, NEAR SYDNEY, NEW SOUTH WALES, AUSTRALIA.

MACHINE FOR GRINDING AND PULVERIZING FRIABLE SUBSTANCES.

Application filed August 22, 1923. Serial No. 658,751.

To all whom it may concern:

Be it known that I, JOHANNES PIETER VAN GELDER, subject of the King of Great Britain, residing at 200 William Street, Granville, near Sydney, New South Wales, Australia, have invented new and useful Improvements in Machines for Grinding and Pulverizing Friable Substances, of which the following as a specification.

10 In the "disintegrator" type of crushing mill in which lumps of friable material are smashed and pulverized by the action of revolving beaters, the granular particles which are too large to pass through the 15 screen in the bottom of the machine casing are retained in the casing, but on account of their small dimensions the beaters act ineffectively on them so that the rate of their reduction is slow and the capacity of the 20 machine is accordingly limited. This class of machine can therefore be utilized with satisfactory economy only with a comparatively coarse screen, in which condition a product having a wide range of gauge is 25 obtained. When the product is required in a finely pulverized condition, subsequent grinding in rolls or other mills is necessary to complete the reduction.

The object of the present invention is to 30 provide means whereby a complete reduction of the product to fine gauge is attainable in a mill of the revolving beater type, and an output obtained which is not less than the output of mixed gauge product which 35 is obtainable from such mills constructed according to present practice. This object is accomplished by introducing a pair of rolls into the upper part of the beater casing so that the granular particles which are 40 whirled by the beater action are caught in the nip of the rolls and such particles reduced by the roll action and are so brought to gauge appropriate to allow them to pass through the delivery screen. The casing is 45 thus rapidly cleared of the coarse and intermediate granular material, so that the operation of the beaters is not clogged and they are freed to operate efficiently.

The accompanying drawing is a trans- 50 verse sectional elevation through a grinder constructed according to the present invention.

The beater shaft 1 is mounted for rotation at a fast speed, usually about 2,000 revolutions per minute, in bearings (not shown).

Upon this shaft an assembly of beater blades 2 of hard metal is mounted in symmetrical order with spacings of greater or less width between the neighbouring beater blades. The lower part of the casing in which the 60 beaters operate is a semi-cylindrical grating or screen 3 the perforations in which are appropriate to the size of the product required to be obtained. The milled product which passes through these perforations is 65 collected in a boot or box 4, below which a conveyor belt may be arranged.

The upper part 5 of the machine casing is lined with replaceable anvil blocks 6 of hard metal, usually having corrugated faces 7. 70 8 is the feed throat to which the lumps of material to be comminuted are delivered from a hopper or belt or otherwise. In the lower part of the neck a replaceable plate of hard metal 9, similar to the plates 6, is 75 disposed. 10 is an access door at one end of the casing.

The upper part of the casing is extended to form a chamber in which two grinder rolls 11 and 12 are rotatably mounted. The 80 spindles carrying these rolls extend through the casing ends and are supported in appropriate bearings. The rolls may be of equal diameter or of differential diameters, and they may be driven at equal peripheral 85 speeds or at differential peripheral speeds. For a machine proportioned as shown in the drawings, with the beaters arranged to revolve at 2,000 revolutions per minute the roll 12 may be driven at 400 to 500 revolu- 90 tions per minute and the roll 11 at any speed from 400 to 800 revolutions per minute or thereabouts.

The bearings carrying the spindle 13 of the roll 12 are contained in slides 14, and 95 pressure is maintained at the roller contacting faces by means of a bearing spring 15 the tension of which is adjustable by means of collar nuts 16 working on a screwed thrust spindle 17. Said spring or 100 springs 15 take an abutment bearing against the yoke 18. 19 are collar nuts adjustable on the spindle 17 for setting back the roll faces to any desired clearance. 20 is a hand lever acting on the back end of the 105 spindle 17 through eccentric trunnions 21, this hand lever serving for rapidly retiring the roll 12 from the roll 11 if at any time it is found necessary to clear the rolls to remove an obstruction. 23 is a scraper plate 110

acting against the face of the roll 12. The direction of rotation of the rolls and the beaters is shown by arrows. 24 is an inspection door.

- 5 Cracked lumps or granular pieces of material are fed into the machine through the throat 8, and on passing into the casing are struck by the rapidly revolving beaters 2 and smashed, a certain proportion being 10 pulverized in this smashing action. The larger pieces are whirled round in the casing and cast or driven against the corrugated liner plates 6 and 9 with the result that the material is thus further broken. 15 Coarse granulated particles which are too large to pass through the perforations in the screen 3 are whirled outwardly by centrifugal action and cast into the nip of the rolls 11 and 12. The material so delivered to the rolls passes between them and is reduced to the required gauge according to the adjustment of the roll pressure and clearance. The material so reduced passes over the top of the roll 11 and down into the casing with the feed, and from the casing passes out through the perforations in the screen 3. The casing of the machine is thus rapidly relieved of the burden of whirling material of intermediate gauge. The 25 rolls operating to take care of this intermediate gauge material, and reduce it to fine gauge and to pass the product directly back to the casing from which it immediately emerges through the perforated 30 screen 3.

35 It is to be understood that the mill may be fitted with two pairs of grinder rolls instead of with one pair only as shown in the drawing. In this case the second pair of rolls would be located at the positions indicated by the dotted circles marked 30 and 31.

40 The same principle of construction may be used in duplex type disintegrator mills in which two bladed shafts are fitted with the blade tips on one of them approaching the blade tips on the other of them. In this case two pairs of grinder rolls would usually be fitted, with the nip of one pair arranged to take the flying particles from one of the beaters, and the nip of the other pair arranged to take the flying particles from the other of the beaters.

45 What I claim as my invention and desire to secure by Letters Patent is:—

- 50 1. A machine for pulverizing friable material, comprising a revoluble beater shaft, beater blades carried on the shaft, a horizontally disposed casing enclosing the beater

55 blades, a grating in the lower part of the casing, a hopper at one side of the upper part of the casing, a shrouded pocket in the upper part of the casing, a pair of rotary grinding rolls mounted in said pocket and disposed with their nip in the path of flight of particles of the material thrown upwards by the beater blades.

60 2. A machine for pulverizing friable material, having a rotary beater shaft, beater blades thereon, rotary grinding rolls mounted above the beater shaft in position to receive the particles of material thrown upwards by the beater blades, and a casing comprising a grating beneath the beater shaft, and a hopper mouth located above 65 the beater shaft and accommodating the grinding rolls in one side thereof.

70 3. A machine for pulverizing friable material, comprising a casing, a grating in the lower portion of the casing, a hopper in the upper portion of the casing, a rotary beater shaft and beater blades in the casing, a pair of pulverizing rolls mounted above the beater shaft in one side of the hopper and in the path of the particles of material thrown upwards by the beater blades, and replaceable anvil blocks 75 mounted in the interior of the casing.

80 4. A machine for pulverizing friable material, comprising a casing, a grating in the lower side of the casing, a hopper extending upwards from one side of the upper part of the casing, a rotary beater shaft and beater blades mounted in the casing, a pair of pulverizing rolls mounted above the beater shaft in one side of the hopper and in the path of the particles of material thrown upwards by the beater blades, and a scraper plate engaging the surface of 85 one of said rolls.

90 5. A machine for pulverizing friable material, comprising a casing, a grating in the lower side of the casing, a hopper extending upwards from one side of the upper part of the casing, a rotary beater shaft and beater blades mounted in the casing, a pair of pulverizing rolls mounted above the beater shaft in one side of the hopper and in the path of the particles of material thrown upwards by the beater blades, spring 95 means for holding the pulverizing rolls in contact with each other and a lever device for releasing the spring pressure between the rolls and for moving the one roll away from the other.

100 In testimony whereof I have signed my name to this specification.

JOHANNES PIETER VAN GELDER.
